UNITED STATES PATENT OFFICE.

JOSEPH HEINEMAN, OF NEW YORK, N. Y.

BUTTON.

1,229,452.

Specification of Letters Patent. Patented June 12, 1917.

Application filed August 16, 1916. Serial No. 115,212.

To all whom it may concern:

Be it known that I, JOSEPH HEINEMAN, a citizen of the United States, residing at the city of New York, in the borough of 5 Bronx and State of New York, have invented certain new and useful Improvements in Buttons, of which the following is a full, clear, and exact description.

One of the objects of my invention is to 10 provide a novel construction of button and means whereby the same may be readily and quickly attached, without stitching, to a garment or other article on which it is to be used, and may be as readily detached there- 15 from.

The invention consists of a button and a keeper, one of said parts comprising a plate having a plurality of arcuate slots therein with enlarged entrance openings, and the 20 other of said parts having a plurality of projections thereon adapted to fit within said slots and provided with shoulders adapted to engage the inner surface of said plate adjacent the surfaces of said slots.

25 The invention also consists in certain features and details of construction and combinations of parts, which will be hereinafter more fully described and claimed.

In the drawing,

30 Figure 1 is a bottom plan view of a button embodying my invention;

Fig. 2 is a sectional view showing the button and its keeper combined and held in locking relation to each other on a strip of 35 fabric;

Fig. 3 is a plan view of the keeper;

Figs. 4 and 5 are detail views of a modified form of keeper;

Fig. 6 is a sectional view of a portion of a 40 modified form of button, such as will be employed in connection with the keeper of Figs. 4 and 5;

Fig. 7 is a bottom plan view of the same, and

45 Fig. 8 is a detail, perspective view of another modified form of keeper.

The body 1 of my improved button may have any shape or configuration of head or exterior surface, but is provided with a metallic base plate 2, formed with the usual hub 3 thereon. Cut in this base plate, preferably within the hub 3, are the arcuate slots 4, 5, the side edges of each slot being parallel, and formed upon the arcs of circles concentric with the circular base plate 2. The end 55 of the slot 4 is enlarged, as at 6, and the end

of the slot 5 is enlarged, as at 7, to provide entrance openings into said slots. After the slots 4 and 5 are produced in the base plate 2, the material of said plate on each side of each slot is pressed, or otherwise shaped, to form the inclined or cam surfaces 8. The surface 8 along the slot 4 gradually rises, or approaches the top of the button, from the entrance opening 6 toward the opposite end of said slot. Similarly, the surface 8 along the slot 5 gradually rises, or approaches the top of the button, from the entrance opening 7 toward the opposite end of said slot. To produce the inclined or cam surfaces 8 the metal of the plate 2 on each side of each of the slots 4 and 5, is arched inwardly toward the body of the button. At the ends of the slots 4 and 5, however, opposite the entrance openings 6 and 7, respectively, the metal of the plate 2 on each side of each of said slots, is reversely or outwardly curved, forming a pocket 9 at the end of the slot 4 and a pocket 10 at the end of the slot 5. These pockets 9 and 10 act as 60 interlocking means between the button and its keeper, as will presently appear.

The keeper comprises a base and a plurality of laterally extending pins or projections thereon, each provided with a shoulder near its end. The form of keeper illustrated in Figs. 2 and 3 of the drawings consist of a disk 11, and two pins or projections 12 secured thereto and extending outwardly therefrom, each of said pins being preferably pointed so that it may be readily forced through the material of the garment to which the button is to be applied. Each of said pins or projections is also provided, near its outer end, with a shoulder 13. The distance between the pins or projections 12 corresponds with the radial distance between the centers of the slots 4 and 5. The heads of said pins formed by the shoulders 13 correspond in diameter with the entrance openings 6 and 7, but are greater in diameter than the slots 4 and 5 themselves.

To apply my improved device, the pins or projections 12 on the keeper are forced through the material 14 of the garment at 105 the location where the button is to be attached, as shown in Fig. 2 of the drawing. The disk 11 is moved into close contact with the inner surface of the material 14 so that the heads or shouldered portions of the pins 110 or projections 12 extend appreciably beyond the opposite surface of the material. The

button 1 is now applied by placing the underside thereof against the material 14, so that the heads of the pins or projections 12 enter the openings 6 and 7 at the ends of the 5 slots 4 and 5. The button is then given a partial rotation. In so turning the button, the shoulders 13 on the pins 12 pass behind the base plate 2, and engage the rear or inner surfaces 8 of said plate along the sides 10 of the slots 4 and 5, with the shanks of said pins projecting through said slots. The surfaces 8 being inclined, the continued turning movement of the button with respect to its keeper, will force said button and keeper 15 closer and closer toward each other, and in tighter and tighter engagement with the material 14 between them. This action continues until the pins or projections 12 reach the opposite ends of the slots 4 and 5, when 20 the shoulders 13 on said pins or projections slip into the pockets 9 and 10, when turning movement of the button with respect to its keeper, in either direction, is resisted. The pockets or recessed portions 9 and 10 co- 25 operate with the headed ends of the pins or projections 12 to hold the two parts of the device in interlocking relation so that the button is held firmly in place on the garment and is practically incapable of accidental removal. When it is desired to remove 30 the button, however, it is merely necessary to turn the head thereof in the direction opposite that just described, with sufficient force to overcome the frictional engagement 35 of the shoulders 13 with the side walls of the pockets 9 and 10, and continue this turning movement until the pins or projections 12 come opposite the entrance openings 6 and 7, when the button may be 40 slipped away from the keeper.

In order to compensate for variations, in the thickness of the material to which my improved button may be applied, so that the two parts of the device may be held in close 45 frictional engagement with the opposite sides of the material, I make the surface of the keeper which engages the material so that it is capable of yielding. One way of accomplishing this result is to form the 50 spring tongues 15 in the disk 11, the said tongues being cut from the material of said disk and sprung upwardly so as to extend beyond the plane of the disk. By the use of these tongues, the two parts of the device 55 may be held in close frictional engagement with materials of varying thicknesses to which the button may be applied.

In Figs. 4 and 5 of the drawing, a modified form of keeper is illustrated. In this 60 construction, all the parts of the keeper are integral. That is to say, the pins or projections 12^a are cut from the sheet metal of which the disk 11^a is made, and are afterward folded up at right angles to the disk 65 11^a, as shown in Fig. 5. The shanks of

these projections between the shoulders 13^a and the disk 11^a are preferably curled, as shown at 16, for strengthening purposes, and the heads of the projections 12^a are preferably given a quarter turn, as shown in Fig. 5, 70 so that the shoulders 13^a may be properly presented to the base plate of the button at right angles to the slots therein.

In Figs. 6 and 7, a slightly modified construction of base plate 2^a is shown, the same 75 being that which will be employed in connection with the modified form of keeper shown in Figs. 4 and 5. It differs from the base plate of Figs. 1 and 2 merely in the shape of the entrance openings 6^a and 7^a, 80 and in the shape of the pockets 9^a and 10^a at the opposite ends of the two slots 4^a and 5^a.

In Fig. 8 of the drawing, another modification of the keeper is illustrated. In this form, the headed projections on the 85 keeper correspond with those shown in Figs. 4 and 5 of the drawings, but instead of having a disk-shaped base with projecting tongues 15 thereon, the base 11^b is of substantially the same width as the headed 90 projections 12^b on the ends thereof and said base 11^b is slightly arched so as to produce the spring or resilient action of the 95 tongues 15.

I claim:

1. The combination of a button and a keeper therefor, one of said parts comprising a plate having a plurality of arcuate slots therein with enlarged entrance openings, and having inclined surfaces extending along said slots above the plane of said plate, and the other of said parts having a plurality of projections thereon adapted to fit within said slots, the said projections having shoulders thereon adapted to engage 105 said inclined surfaces for drawing said parts toward each other when one of them is turned.

2. The combination of a button and a keeper therefor, one of said parts comprising a plate having a plurality of arcuate slots therein with enlarged entrance openings, and having inclined surfaces extending along said slots above the plane of said plate, and the other of said parts having a 110 plurality of projections thereon adapted to fit within said slots, the said projections having shoulders thereon adapted to engage said inclined surfaces for drawing said parts toward each other when one of them 115 is turned, and means engaging said projections for resisting the turning movement of said parts.

3. The combination of a button and a keeper therefor, one of said parts comprising a plate having a plurality of arcuate slots therein with enlarged entrance openings, and having inclined surfaces extending along said slots above the plane of said plate, and the other of said parts having a 125 120 130

yielding base and a plurality of projections thereon adapted to fit within said slots, the said projections having shoulders thereon adapted to engage said inclined surfaces for drawing said parts toward each other when one of them is turned.

4. The combination of a button and a keeper therefor, one of said parts comprising a plate having a plurality of slots therein, and having inclined surfaces extending along the length of said slots above the plane of said plate, and the other of said parts having a plurality of headed projections thereon adapted to fit within said slots, the said projections having shoulders thereon adapted to engage the inclined or cam surfaces on said plate.

5. The combination of a button and a keeper therefor, one of said parts comprising a plate having a plurality of slots therein, the surface of the plate being inclined along the length of and on opposite sides of said slots, and the other of said parts having a plurality of headed projections thereon adapted to fit within said slots, the said projections having shoulders thereon adapted to engage the inclined or cam surfaces on said plate, and means for locking the projections in said slots.

6. The combination of a button and a keeper therefor, one of said parts comprising a plate having a plurality of slots therein, the surface of the plate being inclined along the length of and on opposite sides of said slots, and the other of said parts comprising a base having a yielding surface and provided with a plurality of headed projections adapted to fit within said slots, the said projections having shoulders thereon adapted to engage the inclined or cam surfaces on said plate.

7. The combination with a button comprising a plate having a plurality of concentric arcuate slots therein, the said slots having enlarged entrance openings, and the surface of the plate being inclined along the length of and on opposite sides of said slots, of a keeper having headed projections thereon adapted to pass through said entrance openings, the said projections having shoulders thereon adapted to engage

and ride upon the inclined surfaces of said plate.

8. The combination with a button comprising a plate having a plurality of concentric arcuate slots therein, the said slots having enlarged entrance openings, and the surface of the plate being inclined along the length of and on opposite sides of said slots, of a keeper having headed projections thereon adapted to pass through said entrance openings, the said projections having shoulders thereon adapted to engage and ride upon the inclined surfaces of said plate, and means for locking said projections in said slots.

9. The combination with a button comprising a plate having a plurality of concentric arcuate slots therein, the said slots having enlarged entrance openings, and the surface of the plate being inclined along the length of each of said slots and provided with pockets or depressions at the ends of the slots opposite their respective entrance openings, of a keeper having headed projections thereon adapted to pass through said entrance openings, the said projections having shoulders thereon adapted to engage and ride upon the inclined surfaces of said plate and to fit within said pockets, as and for the purpose set forth.

10. The combination with a button comprising a plate having a plurality of concentric arcuate slots therein, the said slots having enlarged entrance openings, and the surface of the plate being inclined along the length of and on opposite sides of said slots, of a keeper comprising a base having spring tongues thereon and having headed projections adapted to pass through said entrance openings, the said projections having shoulders thereon adapted to engage and ride upon the inclined surfaces of said plate, and means for locking the button and keeper against relative turning movement.

In witness whereof, I subscribe my signature, in the presence of two witnesses.

JOSEPH HEINEMAN.
